FIRE NOZZLE

John O. Hruby, Jr., Burbank, Calif., assignor to John Drew, Gerald W. Frasier, and John O. Hruby, Jr., copartners, doing business as Irrigation Engineering & Manufacturing Co.

Application November 4, 1955, Serial No. 545,005

14 Claims. (Cl. 239—237)

This invention relates to fluid discharge devices and more particularly to nozzles which are especially well suited for fire-fighting purposes.

By way of introduction to this specification and serving as a brief summary indicating the nature and substance of the invention, the following is quoted from Bulletin No. 92, dated December 15, 1939, by the National Board of Fire Underwriters, New York, N.Y., entitled "Spray Application of Water":

"There are several types of fires where engineering indicates that the solid stream, so commonly used in the past operations of fire departments, is not well adapted to fire extinguishment. These fires may be listed roughly as:

"Oil, grease, tar and other flammable liquids.

"Smoky fires, especially where interior fire fighting is in order.

"Protecting an exposed building from an adjoining fire.

"A widely spread fire of low heat intensity.

"Chimney or grease duct fires.

"Grass or underbrush fires.

"In all of these fires one of the prime requisites is to reduce the temperature of the ensuing gases and smoke, so that when these heated products of combustion reach a point where they have sufficient oxygen, they will not ignite. Another object is to cool down the unburned material, which, being exposed to these heated gases, will later ignite if not kept below the ignition point. A further and very important item in fire fighting is to clear up the smoke to a point where hindrance to actual attack of the fire will not exist. Smoke prevents the firemen from locating the burning material, which often may be of small amount. Smoke also may drive the firemen out.

"It is a well known fact that water absorbs not only heat but also many of the toxic gases of a fire, and tends to clear away the smoke, but it does this most effectively when broken up into fine particles. For a number of years this value of minute drops of water has been appreciated in Europe, and diffusers or spray nozzles have been used in interior fire fighting, especially in dwelling fires. In recent years this practice has been tried out in many American fire departments, through the use of fog nozzles, of various designs. These were developed first as means of combating oil fires; the principle of the nozzle is to discharge a fine mist or fog of water particles, and to do this it is generally desirable to use high nozzle pressures, as otherwise there is not sufficient carry to the stream. As the use of these nozzles becomes more general, each department trying them out realizes the possibilities of their use. As with all other fire department equipment such nozzles are not suitable for all types and kinds of interior fires. Primarily they are limited to fires of low heat intensity; to those where the smoke is dense and there is little deeply embedded fire whose heat will change the mist into steam before it reaches the bed of embers.

2

"There is another form of nozzle which has not yet been perfected which will be the ultimate type to be used on interior fires which have progressed beyond the stage where the fog nozzle will be effective. This is a nozzle of larger calibre than the $\frac{1}{2}$ -inch fog nozzle generally found so satisfactory for fires of small magnitude. The larger calibre is necessary to give sufficient water to cool down the highly heated gases and burning material and reach the seat of the fire. Such a nozzle should not produce a fog but should give a heavy broken-up stream resembling more a rain than a fog, with the drops of sufficient size to give a carry to the stream of 30 to 50 feet. Nozzles of this kind, operated from a ladder into a window, or possibly from a water tower or ladder pipe, where the nozzle is struck into the window, should reduce temperatures enough to permit entry to the floor. Somewhat this same use of water, but in an ineffective way, is the attempt of firemen to produce a spray by partially closing a shut-off nozzle or by playing the stream against the ceiling. Much more effective work would be obtained by the use of a special nozzle."

It is an object of this invention to provide a nozzle which meets the requirements set forth in the last paragraph of the above quotation. The nozzles of this invention are as completely effective and advantageous in extinguishing fires as was forecast back in 1939 by the National Board of Fire Underwriters.

Further objects and advantages of the invention will appear during the course of the following part of this specification, wherein the details of construction and mode of operation of a preferred embodiment of the invention are described with reference to the accompanying drawings, in which:

Fig. 1 is a side elevation of a nozzle embodying the invention, the left-hand half of the nozzle and the upper end thereof being shown in central longitudinal section;

Fig. 2 is a plan view of the orifice end of the nozzle;

Fig. 3 is a central longitudinal section on an enlarged scale through a water discharge element or sub-assembly 40 of the nozzle, taken on line 3—3 of Fig. 2;

Fig. 4 is a cross-section on an enlarged scale through the discharge element taken on line 4—4 of Fig. 3; and

Fig. 5 is a cross-section on an enlarged scale through the discharge element taken on line 5—5 of Fig. 3.

Referring to the drawing in greater detail, reference numeral 10 designates, generally, a nozzle embodying the invention, the same comprising a tubular body 11, shown as a hollow elongate cylinder of circular cross-section, having a flow passage 12. The lower end of the body is externally threaded at 13 for attaching the same to a socket designated generally by numeral 14, such socket 14 comprising a reducing coupling 15 and a reducing bushing 16, by means of which the nozzle is adapted for connection to the water discharge end of a fire hose (not shown), the reducing bushing having a conventional washer 17 seated therein for forming a water-tight connection between the nozzle and hose.

A cap 19 covers the water discharge end of the nozzle. It is fixed on the end of the body 11 as by screw thread 60 connection 20. The cap 19 has a central orifice 21 formed therein, for producing a solid core of small diameter for the broken-up stream produced by the nozzle. In the illustrated embodiment the orifice 21 is circular in general outline and the walls defining it are irregular, i.e. screw threads 22 are formed therein for disrupting the wall of the stream core.

Spaced around the central orifice is a plurality of openings 24 formed in the cap, there being six such openings in the illustrated embodiment, the same being uniformly 70 spaced apart in an annularly arranged series intermediate the central orifice and the rim of the cap. These openings are adapted, by means of screwthreads formed in the

walls thereof, to receive respective stream break-up discharge devices or sub-nozzle assemblies designated generally by reference numeral 26.

The discharge devices 26 are of the general type illustrated and described in Letters Patent of the United States Nos. 2,589,942 and 2,639,191, issued to me on March 18, 1952, and May 19, 1953, respectively. For the nozzle 10 the discharge devices 26 are constructed to include some of the improved features of a nozzle of the same general type as above mentioned and on which I am making application for Letters Patent contemporaneously herewith.

Referring to Fig. 3, wherein the details of construction of one discharge device 26 are best shown, it is seen that such device comprises a tubular body 29 defining a passage 30 extending axially therethrough. Arranged longitudinally in the passage is a stem 31, the outside diameter of which is less than the diameter of the passage whereby the stem is freely rotatable and moveable longitudinally in the passage. The body has a plurality of apertures 32 formed therein, the same being inclined (tangent in the illustrated embodiment) with respect to the radii of the passage 30, for admitting water to the passage and causing such water to spiral, thereby to rotate the stem on its axis and cause the stem to gyrate around in the passage with the axis of the stem being inclined with respect to the axis of the passage.

As the stem is rotated by the swirl of water in the passage, it contacts and thus rolls on an edge 34 of a bearing sleeve 35 defining the lower end of the passage. The bearing sleeve is preferably formed of oil impregnated sintered bronze. The upper portion of the stem likewise contacts and thus rolls around the walls defining the upper portion of the passage, the same being frusto-conical in configuration to provide increased contact surface with the stem and to permit gyration of the stem in a greater circle.

The inside wall of the body has an annular recess 37 formed therein proximate the lower end of the body. This recess is formed as by making a counterbore 38 in the lower end of the body for receiving the bearing sleeve 35 force-fitted into the counterbore. The bearing sleeve is shorter in its axial dimensions than the counterbore, thereby to define the lower shoulder of the recess. Such recess serves to collect sand and other foreign particles carried in the water and thus prevents the same from dropping down into the passage and becoming lodged between the stem and the bearing sleeve, at which position such sand or foreign particles would restrict free rolling of the stem around the edge 34 of the bearing sleeve.

To maintain the stem within the passage against being carried out through the outlet end of the passage by the swirling stream of water, there is a collar 40 anchored around the lower end of the stem as by detent means shown at 41. A washer 42 is positioned around the stem between the collar and the bearing sleeve, the washer being freely rotatable on the stem.

Reference numeral 44 designates the axially extending passage through the stem, the same being open at the lower end to provide for a flow of water from the passage 12 of the nozzle. At its upper end the stem is flattened and flared outwardly to form an elongate orifice 46. By being flared, the stem is prevented from dropping downwardly out through the body passage, i.e. when no water is passing through the discharge device, the stem drops downwardly in the passage until the flared end of the stem is received in the frusto-conical upper portion of the passage as shown in a full line position thereof in Fig. 3. When water passes through the discharge device, the stem extends upwardly in the passage as represented by the broken line position thereof shown at 47.

From the above description, it will be apparent that water flows through each of the discharge devices 26 in two separate paths, i.e. through the stem 31 and around the stem. Water from the stem orifice is discharged as a

fan-shaped stream which immediately upon discharge is disrupted and broken up as a result of the rotation of the stem on its axis and of gyration of the stem within the body passage. Such gyration of the stem furthermore breaks up the stream of water flowing out from the discharge device around the stem and the flared end of the stem increases the extent of stream break-up. The force of the water in each of the two broken-up streams, one initially at least partly within the other, causes further breaking up of the outer stream, with the final result that water is discharged from device 26 in a stream of discrete and well distributed drops as distinguished from a fine spray or fog. It is found, too, that these discrete drops, i.e. like rain drops, have relatively high carrying power, so that they carry to a relatively great distance from the nozzle.

With the discharge devices 26 arranged around the central orifice 21, each of the broken-up streams of discrete drops are further broken up by each other. These outer streams then impinge upon the centrally disposed solid stream from orifice 21, causing the solid core to break up at some distance from the nozzle, with the final result that a combined stream of discrete drops having high carrying power is produced.

Should it be desired to restrict the cross-sectional area of the combined streams from the nozzle, there is provided an outer sleeve 49 around the nozzle body 11 and slideable longitudinally on the body to a selected position where it will limit the diameter of the nozzle stream as desired. To secure the outer sleeve 49 at a desired extended position on the nozzle body, the sleeve has an inside collar 50 which in the illustrated embodiment is suitably secured in the sleeve 49 as by screw 51. A wing screw 52 is provided for tightening the sleeve to the body. The collar 50 also prevents inadvertent removal of the sleeve 49 from the body by being engageable with a flange 53 on the cap 19.

The nozzle 10 includes means for filtering solids carried in the water supply flowing through the nozzle and for directing such solids into the solid core portion of the nozzle stream. Such filtering means comprises a conical screen 55 formed of wire mesh and arranged co-axially in the nozzle body, with the apex thereof being directed toward the cap 19. The screen 55 is bent radially outwardly at its base to form a flange 56 for securing the screen to the inside end of the body. As the water flows through the body, solid particles carried in the water are retained by the screen and thence travel along the screen wall towards the screen apex. Such apex is open, as shown at 57, in alignment with the central orifice 21 of the cap, whereby the filtered solids are confined to that portion of the stream which is discharged as a solid core, and thereby prevented from entering the discharge devices 26. In the illustrated embodiment the opening 57 of the screen is spaced inwardly from the cap. However, it is contemplated herein that the screen may be attached at its apex end to the cap with the periphery of the opening 57 circumjacent the orifice 21 of the cap, thereby to insure against any probability that foreign particles carried in the central portion of the flow of water will enter the discharge devices 26.

A fire nozzle embodying this invention produces a heavy broken-up stream of discrete drops resembling more a rain than a fog, with the drops of sufficient size to give a carry to the stream of about 100 feet, depending, of course, upon the size of the nozzle and upon the pressure of water supplied to the nozzle. The effectiveness and efficiency of the streams produced by these nozzles in quickly quenching fires is so remarkable and surprising as to suggest that even the National Board of Fire Underwriters, which long ago recognized the need for a fire nozzle of the type herein described for producing the results which it imagined, would be amazed by the results actually obtained. These nozzles permit fire fighters to combat fires with broken-up streams of

the type herein described, at safe distances from a fire. Also, it is important to note that these nozzles, when made to a relative size corresponding to that of nozzles producing solid streams and requiring two and sometimes more men to handle and control the same, may be handled and controlled effectively by but one man.

While I have herein shown and described my invention in what I have conceived to be the most practical and preferred embodiment, it is recognized that departures may be made therefrom within the scope of my invention which is not to be limited to the details disclosed herein, but is to be accorded the full scope of the claims so as to embrace any and all equivalent structures.

Having described my invention, what I claim as new and desire to secure by Letters Patent is:

1. A fluid discharge device comprising a cap having an orifice extending therethrough, a plurality of fluid discharge sub-assemblies positioned in the cap and spaced around and proximate said orifice, each sub-assembly comprising a tubular body providing a fluid passageway through the cap, said body having an aperture formed therein for admitting fluid into the body, said aperture being inclined with respect to the radii of the body for causing swirling of fluid in the body, and an elongate stem arranged longitudinally in the body, stop means on the stem engageable with the body for retaining the stem in the body, said stem being rotatable on its axis and gyratable in the body with the axis of the stem inclined with respect to the axis of the body.

2. A nozzle comprising a main tubular body, a cap on one end of the body, a plurality of fluid discharge sub-assemblies secured in the cap, each sub-assembly comprising a tubular sub-body extending into the main body and having an outlet opening and providing a fluid passageway through the cap, each sub-body having an aperture formed in that portion of the sub-body extending into the main body for admitting fluid into the sub-body, said aperture being inclined with respect to the radii of the sub-body for causing swirl of fluid around in and out from the sub-body, a plurality of elongate tubular stems arranged longitudinally in the sub-bodies respectively and projectable outwardly of the outlet opening of its sub-body, each stem having an opening in each end portion thereof respectively, each stem being rotatable on its axis and gyratable in its respective sub-body, stop means on each stem engageable with its respective sub-body for retaining the stems in their respective sub-bodies, and an outer sleeve around the main body adapted to extend outwardly beyond said cap.

3. A nozzle comprising a main tubular body adapted for connection at one end thereof to a fluid supply conduit, a cap covering the opposite end of the body, the cap having an orifice extending therethrough and disposed substantially centrally of the cap, a plurality of fluid discharge sub-assemblies secured in the cap and spaced around said orifice, each sub-assembly comprising a tubular sub-body extending into the main body and having an outlet opening and providing a fluid passageway through the cap, each sub-body having an aperture formed in that portion of the sub-body extending into the main body for admitting fluid into the sub-body, said aperture being inclined with respect to the radii of the sub-body for causing swirl of fluid around in and out from the sub-body, a plurality of elongate tubular stems arranged longitudinally in the sub-bodies respectively and projectable outwardly of the outlet opening of their respective sub-bodies, each stem having an opening in each end portion thereof respectively, each stem being rotatable on its axis and gyratable in its respective sub-body, and stop means on each stem engageable with its respective sub-body for retaining the stems in their respective sub-bodies.

4. A nozzle comprising a main tubular body adapted for connection at one end thereof to a fluid supply conduit, a cap covering the opposite end of the body, the

cap having an orifice extending therethrough and disposed substantially centrally of the cap, a plurality of fluid discharge sub-assemblies secured in the cap and spaced around said orifice, each sub-assembly comprising a tubular sub-body extending into the main body and providing a fluid passageway through the cap, each sub-body having an inclined aperture formed in that portion of the sub-body extending into the main body for admitting fluid into the sub-body and for causing swirl of fluid around in and out from the sub-body, a plurality of open-ended tubular stems arranged longitudinally in the sub-bodies respectively, each stem being rotatable on its axis and gyratable in its respective sub-body, means for retaining the stems in their respective sub-bodies, and filtering means within and extending across the main body, said filtering means having an opening formed therein in alignment with the said orifice.

5. A nozzle according to claim 4 in which the filtering means comprises a conical screen having an apex, said screen being arranged in the main body with its apex directed toward said cap, and said opening being formed in the apex of the screen.

6. A nozzle comprising a main tubular body, a cap covering one end of the body, the cap having an orifice extending therethrough and disposed substantially centrally of the cap, a plurality of fluid discharge sub-assemblies secured in the cap and spaced around said orifice, each sub-assembly comprising a tubular sub-body having an outlet opening therein and providing a fluid passageway through the cap, each sub-body having an inclined aperture formed in that portion of the sub-body extending into the main body for admitting fluid from the main body into the sub-body and for causing swirl of fluid around in and out from the sub-body, a plurality of open-ended tubular stems arranged longitudinally in the sub-bodies respectively and projectable outwardly of the outlet opening of their respective sub-bodies, each stem being rotatable on its axis and gyratable around in its respective body, the stems being flattened at their outlet ends to provide respective elongate transversely extending orifices for the stems, and means operatively associated with respectively sub-bodies and stems for preventing said stems from being carried out from their sub-bodies.

7. A nozzle according to claim 6 including an outer sleeve around the main body, said sleeve being movable axially on the main body, and stop means for preventing removal of the sleeve from the main body.

8. A fluid discharge device comprising a tubular body having an outlet opening at one end thereof, the body having an inclined aperture formed therein for admitting fluid from outside the body to the interior of the body and for causing swirl of fluid around in the body and out from said opening, an open-ended tubular stem arranged longitudinally in the body, the stem being flattened at that end thereof proximate said opening to provide an elongate transversely extending orifice for the stem, and stop means on the stem engageable with the body for retaining the stem in the body against being carried out through said opening, said stem being rotatable on its axis and gyratable around in the body.

9. A fluid discharge device comprising a body having inside walls defining a passageway therein and having an outlet opening at one end thereof, the body having a plurality of apertures formed therein for admitting fluid to said passageway, said apertures being inclined with respect to said passageway to cause fluid in the passageway to spiral and pass out through said opening, the inside walls of the body adjacent said opening being inclined outwardly whereby said opening is of greater area than the cross-sectional area of that part of the passageway beyond said inclined walls, an elongate open-ended tubular stem arranged longitudinally in the passageway and projectable outwardly of said outlet opening, said stem being movable longitudinally in the passageway

and rotatable on its axis and gyratable around in the passageway with the axis of the stem inclined with respect to the axis of the passageway, the stem being flattened and flared at that end thereof proximate said opening to provide an elongate transversely extending orifice for the stem, stop means operatively associated with the stem and body for preventing removal of the stem out through said opening, and said flared end of the stem being of a size sufficient to be received in but not passable through that part of the passageway defined by said inclined walls.

10. A nozzle comprising a body having a passageway extending therethrough providing a fluid inlet opening, a cap on the body extending transversely of the passageway, the cap having an orifice extending therethrough and disposed substantially centrally of the cap, the cap having a plurality of outlet openings formed therein and spaced around said orifice, stream break-up means disposed in respective outlet openings, and filtering means within the body and extending across the passageway, said filtering means having an opening formed therein in alignment with said orifice.

11. A nozzle comprising a body having a passageway extending therethrough providing a fluid inlet opening, a cap on the body extending transversely of the passageway, the cap having an orifice extending therethrough and disposed substantially centrally of the cap for flow of fluid out from said passageway, the cap having a plurality of outlet openings formed therein for flow of fluid out from said passageway, said outlet openings being spaced around said orifice, stream break-up means disposed in respective outlet openings, and an outer sleeve around the body, said sleeve being movable longitudinally on the body to selected positions extending beyond the cap, whereby said orifice emits a solid stream of fluid from the nozzle body and said solid stream constitutes a carrying stream for the broken-up streams emitted from said stream break-up means, and said sleeve serves to deflect said broken-up streams toward said carrying stream.

12. A nozzle comprising a body having a passageway extending therethrough providing a fluid inlet opening, a cap on the body extending transversely of the passageway, the cap having an orifice extending therethrough and disposed substantially centrally of the cap, the cap having a plurality of outlet openings formed therein and spaced around said orifice, stream break-up means disposed in respective outlet openings, filtering means within the body and extending across the passageway, said filter-

ing means having an opening formed therein in alignment with said orifice, and an outer sleeve around the body, said sleeve being movable longitudinally on the body to selected positions extending beyond the cap.

- 5 13. A nozzle comprising a body having a passageway extending therethrough providing a fluid inlet opening, a cap on the body extending transversely of the passageway, the cap having an orifice extending therethrough and disposed substantially centrally of the cap, the cap having a plurality of outlet openings formed therein and spaced around said orifice, stream break-up means disposed in respective outlet openings, and a conical screen within the body and extending across the passageway, said screen having its apex directed toward the cap and an opening formed in the apex of the screen in alignment with said orifice.
- 10 14. A nozzle comprising a main tubular body adapted for connection at one end thereof to a fluid supply conduit, a cap covering the opposite end of the body, the cap having an orifice extending therethrough and disposed substantially centrally of the cap, the walls defining said orifice being mutilated for disrupting the walls of a stream passing through the orifice, a plurality of fluid discharge sub-assemblies secured in the cap and spaced around said orifice, each sub-assembly comprising a tubular sub-body extending into the main body and providing a fluid passageway through the cap, each sub-body having an inclined aperture formed in that portion of the sub-body extending into the main body for admitting fluid into the sub-body and for causing swirl of fluid around in and out from the sub-body, a plurality of open-ended tubular stems arranged longitudinally in the sub-bodies respectively, each stem being rotatable on its axis and gyratable in its respective sub-body, and means for retaining the stems in their respective sub-bodies.
